UNITED STATES PATENT OFFICE.

ALFRED R. WITWER, OF SABETHA, KANSAS.

ELECTRIC SWITCH.

1,165,479.

Specification of Letters Patent. Patented Dec. 28, 1915.

Application filed September 28, 1914. Serial No. 863,971.

To all whom it may concern:

Be it known that I, ALFRED R. WITWER, a citizen of the United States, residing at Sabetha, in the county of Nemaha and State of Kansas, have invented a new and useful Electric Switch, of which the following is a specification.

The device forming the subject matter of this application is an electric switch and the 10 object of the present invention is to provide a device of this type including a movable member which is actuated by a permutation mechanism, so that a conducting element on the movable member is brought into contact 15 with an electrical terminal, thereby to close a circuit, the construction being such that the movable member can be actuated only by a person in possession of a predetermined combination adapted to be set off by 20 the permutation means.

It is within the scope of the invention to improve generally and to enhance the utility of devices of that type to which the present invention appertains.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

30 35 In the accompanying drawings:—Figure 1 shows the invention in front elevation; Fig. 2 is a longitudinal section on the line 2—2 of Fig. 3; Fig. 3 is a cross section on the line 3—3 of Fig. 2; Fig. 4 is a fragmental section of the inner disk and attendant parts; Fig. 5 is a fragmental plan of the cam disk, the view depicting a modification.

In carrying out the present invention there is provided a supporting structure 45 which may be a box-like casing 1 preferably fashioned from insulating material. Upon the rear wall of the casing 1 is mounted a binding post 2 or the like adapted to receive a conductor 3, the binding post 2 affording an electrical terminal 4 which is accessible 50 from the interior of the casing 1. A pin 5 fashioned from conducting material is mounted to slide in the front wall of the casing 1 and is aligned horizontally with the 55 terminal 4, the pin 5 having an exposed head 6 which preferably is fashioned from

insulating material. The pin 5 may carry a binding post 7 or the like adapted to receive a conductor 8.

Journaled for rotation in the casing 1 and 60 extended transversely thereof is a shaft 9 upon which is mounted a disk 11 held in place by nuts 10 threaded on the shaft 9. Secured to the outer end of the shaft 9 is a 65 permutation disk 12 inscribed with characters 14 adapted to coact with any one of a series of indices 15 on the outer face of the casing 1 as Fig. 1 will make manifest.

The disk 12 and the indices 15 constitute an indicator mechanism whereby the shaft 70 9 may be set in adjusted positions.

Mounted to reciprocate in the casing 1 is a movable member preferably taking the form of a bar 16, the bar 16 being fashioned from insulating material. The bar 16 is 75 provided with a longitudinal guide in the form of a slot 17 which receives the shaft 9, the construction being such that the bar is mounted to reciprocate on the shaft. The upper end of the bar 16 is disposed within a 80 keeper 18 attached to the rear wall of the casing 1. Extended through the bar 16 is a bridge pin 19 fashioned from conducting material.

A spring 20 is secured to the casing 1 and 85 bears against one side of the bar 16. The spring 20 may be retracted away from the bar 16 by means of a releasing member 21.

Mounted on the disk 11 are cam strips 22, 23 and 24. A strip 25 is located adjacent 90 one end of the strip 22, a strip 26 is located adjacent one end of the strip 23, and a strip 27 is located adjacent one end of the strip 24. Projecting from the movable member or bar 16 is a pin 28 adapted to coact with 95 the cam strips in a manner to be pointed out hereinafter.

Suppose that the parts are positioned as shown in Fig. 2 and that, through the medium of the permutation disk 12, the shaft 9 100 and the disk 11 are rotated. Let it be supposed, further, that the initial rotation of the shaft 9 takes place in the direction of the arrow X in Fig. 2. Then, as the pin rides along the strip 22, the bar 16 will be 105 raised through a step determined by the eccentricity of the cam strip 22. Then, if the disk 11 is rotated in the direction of the arrow Y, the bar 16 will be lifted another step by the action of the cam strip 23. 110 Finally, if the disk 11 be rotated in the direction of the arrow Z, bar 16 will be raised

by the strip 24, and the pin 19 in the bar will be lined up with the fixed terminal 4 and the movable terminal 5. If the movable terminal 5 now be pushed inwardly, a circuit will be closed, comprising the conductor 3, the terminal 4, the bridge pin 19, the pin 5, and the conductor 8.

As the bar 16 is raised step by step, the same will be held elevated by the action of 10 the spring 20. Though the medium of the releasing member 21, the spring 20 may be pulled out of contact with the bar 16 at any time, whereupon the bar will drop and by giving the disk 11 a turn or two, the parts 15 will be restored to the positions shown in Fig. 2.

If disk 11 be turned too far in the direction of the arrow X, the strip 25 will engage the pin 28 and retract bar 16. The 20 strip 26 coacts in a similar manner with the strip 23 and the relations existing between the strips 24 and 27 will be clearly understood from the foregoing.

The operation of a permutation lock 25 mechanism is clearly understood by those skilled in the art and it will be appreciated, when Fig. 1 is examined, that the amount of rotation imparted to the shaft 9 at each step may be determined by bringing the 30 proper character 14 upon the permutation disk 12 opposite to one of the indices 15.

The combination may be changed at any time by loosening the nuts 10 and shifting the disk 11 on the shaft 9.

35 In Fig. 5, the cam disk is denoted by the numeral 100 and the numeral 101 indicates one of the cam strips. Screws 102 or any other suitable fastening means may be employed for connecting the cam strips 101 40 detachably with the disk 100, the end in view being to permit a shifting and an interchanging of cam strips, thereby to change the combination.

Having thus described the invention, 45 what is claimed is:

1. In a device of the class described, a casing; a shaft journaled for rotation in the casing; a bar having a slot through which the shaft passes, the slot being elongated to 50 permit the bar to move endwise with the shaft as a guide; guiding means on the casing and coacting with the bar to hold the same for right line movement; a disk secured to the shaft; coöperating elements 55 on the disk and the bar which coact to move the bar endwise when the disk and the shaft are rotated; indicator mechanism for setting the shaft in adjusted positions; a conducting element on the bar; and an electric 60 terminal with which the conducting element coacts when the bar is moved endwise.

2. In a device of the class described, a supporting structure; a movable member thereon and having a conducting element; permutation mechanism operatively connected with the movable member to advance the movable member to a predetermined position; and an electrical terminal on the supporting structure and movable by an operator to contact with the conducting element after the movable member has assumed said predetermined position.

3. In a device of the class described, a supporting structure; an electrical terminal thereon; a movable electrical terminal on the supporting structure and aligned with the first specified terminal; a movable member mounted on the supporting structure and provided with a bridge means adapted to be aligned with the terminals; and permutation mechanism operatively connected with the movable member to advance the same and to bring the bridge means into alignment with the terminals.

4. In a device of the class described, a supporting structure; an electrical terminal thereon; a movable member mounted on the supporting structure and having a conducting element adapted to coact with the terminal; a shaft journaled in the supporting structure; a permutation disk connected therewith; a projection on the movable member; a disk carried by the shaft; and cam strips on the last specified disk, the cam strips being adapted to coöperate with the projection, thereby to actuate the movable member and to dispose the conducting element and the terminal in coacting relation.

5. In a device of the class described, a supporting structure; an electrical terminal carried thereby; a movable member mounted to reciprocate on the supporting structure; a conducting element in the movable member and adapted to coact with the terminal; yieldable means for holding the movable member against movement; means for releasing the yieldable means; a projection on the movable member; a shaft journaled in the supporting structure; a disk carried by the shaft; cams strips on the disk and adapted to coöperate with the projection, thereby to actuate the movable member and to bring the conducting element and the terminal into coacting relation; and a permutation mechanism carried by the shaft.

In testimony that I claim the foregoing as my own, I have hereto affixed my signature in the presence of two witnesses.

ALFRED R. WITTWER.
